CLAIM

What is claimed is the ornamental design for a media sharing device with graphical user interface, as shown and described herein.

DESCRIPTION

FIG. 1 is a front view of a media sharing device with graphical user interface according to a first embodiment; and,

FIG. 2 is a front view of a media sharing device with graphical user interface according to a second embodiment. The sharp-cornered rectangle shown within the outermost round-cornered rectangle illustrates the perimeter of the display screen of the media sharing device. The outermost round-cornered broken-line rectangle illustrates a media sharing device. The remaining broken lines illustrate portions of the display screen and graphical user interface. The broken lines form no part of the claimed design, with exception of the longer-dashed lines depicting a square-shaped feature surrounding the small solid-line circle near the lower center of the screen, which are included in the claimed design.
